Primary Examiner — Karen S Acker*Assistant Examiner* — Omeed Agilee(74) *Attorney, Agent, or Firm* — Muncy, Geissler, Olds & Lowe, P.C.**(57) CLAIM**

The ornamental design for a clamp for digital products, as shown and described.

DESCRIPTION

FIG. 1 is a perspective view of a clamp for digital products showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a left side elevational view thereof shown in a position of use holding unclaimed environmental material drawn in broken line.

The parts of the clamp for digital products drawn in broken line in FIGS. 1-8 depict portions of the article that form no part of the claimed design.

1 Claim, 8 Drawing Sheets(56)
